UNITED STATES PATENT OFFICE.

ALFRED N. BESSESEN, OF MINNEAPOLIS, MINNESOTA.

SYRINGE.

1,223,243.

Specification of Letters Patent. Patented Apr. 17, 1917.

Application filed June 15, 1916. Serial No. 103,781.

To all whom it may concern:

Be it known that I, ALFRED N. BESSESEN, a citizen of the United States, residing at Minneapolis, in the county of Hennepin and State of Minnesota, have invented certain new and useful Improvements in Syringes; and I do declare the following to be a full, clear, and exact description of the invention, such as will enable others skilled in the art to which it appertains to make and use the same.

This invention relates to certain new and useful improvements in syringes designed more particularly for the hypodermic injection of anesthetic or other fluids into the tissues of the human body, or for such other use where a more or less continuous injection of a considerable quantity of fluid may be desired without the necessity of withdrawing the syringe.

One object of the invention is to provide a syringe of this character which can be fed or supplied by one or more containers.

Another object of the invention is to provide inwardly and outwardly opening valves in the inlet and outlet passages respectively of the syringe whereby the barrel of the same can be refilled without removing the needle from the body.

A further object of the invention is to generally improve upon devices of this character by the provision of a simple, comparatively strong, durable and inexpensive construction which will be efficient and reliable in operation and well adapted to the purpose for which it is designed.

With these and other objects in view, the invention consists of certain details of construction, and the combination and arrangement of parts as will be hereinafter fully described and claimed.

In the accompanying drawings, in which like parts are designated by similar reference characters throughout the several views:

Figure 1 represents a side elevation of a syringe constructed in accordance with this invention, showing a pair of medicament containing receptacles connected to the same;

Fig. 2 is a central longitudinal sectional view through the barrel of the syringe;

Fig. 3 is an elevation of one end of the barrel, the cap to which the needle is attached being removed; and,

Fig. 4 is a sectional view taken on the plane of the line 4—4 of Fig. 1.

Referring more particularly to the drawings, the reference numeral 1 represents a cylindrical or tubular barrel, which may be constructed of any suitable material, but preferably of metal or glass. One end of the barrel 1, which may be designated as the rear end, is internally threaded as at 2 for the reception of an externally threaded plug 3, the latter closing this end and being provided with a centrally arranged opening 4 therein through which extends a stem 5 carried by a plunger 6 disposed within the interior of the barrel. The free end of the stem 5 is provided with a suitable handle 7 between the inner side of which and the outer end of the cap 3 is disposed a coil spring 8, the purpose of which is to normally hold said plunger in its retracted position.

Extending laterally from one side of the barrel 1 at the rear end thereof is a handle member 9, while extending similarly from the diametrically opposite side of the barrel is a stem 10, said member 9 and stem 10 being adapted to be engaged by the fingers of the person using the device when depressing the plunger. The free end of the stem 10 is provided with a plurality of comparatively short stems or nipples 11 having passages 12 extending therethrough which intersect a passage 13 extending through the stem 10. The stem 10 at the point of intersection of the passages 12 with the passage 13 is provided with a transversely extending opening 14 in which is mounted in any suitable manner a rotary plug or valve 15, the latter having a passage 16 extending therethrough, said passage 16 being adapted to open one of the passages 12 into communication with the passage 13, whereby the desired medicament may be fed or supplied by the feed pipes or tubes 17 from a plurality of containers 18.

The forward end of the barrel 1 is reduced in diameter and is externally threaded to provide for the reception of the internally threaded cap 19 to which the needle 20 or other nozzle member is connected in the usual manner. As shown clearly by Figs. 2 and 3 of the drawings, formed integrally with the forward end of the barrel 1 is a head 20', which is provided with a recess 21 having a valve seat 22 arranged in one side thereof, in which is disposed a ball valve 23. The valve seat 22 registers with one end of a passage 24 which extends longitudinally through the wall of the barrel 1 and com-

2
municates with the passage 13 which extends through the aforesaid stem 10. The recess 21 communicates with the interior of the barrel by a central opening 25 in the 5 head 20', and with a valve seat 26 arranged in a notch 27 in one edge of the outer side of the head 20' by a passage 28. Arranged in the valve seat 26 is a ball valve 29. The cap 19 and the head 20' with its recess 21 and notch 27 coöperate to form suitable compartments in which are retained these inwardly and outwardly opening valves 23 and 29 respectively. Extending through the cap 19 and needle 20 is an outlet passage 30 10 through which the contents of the barrel are forced when the plunger 6 is depressed.

In operation, the handle 7 is depressed, thereby forcing the plunger 6 to its forward-most position within the interior of the barrel 1, which movement forces the air contained therein through the opening 25, the 20 passages 28 and 30, and out through the needle 20, it being understood that the ball valve 29 will be thereby moved to its opened position. Upon releasing the pressure upon the handle 7, the spring 8 will force the same to its outermost position, thereby closing the ball valve 29, opening the ball valve 23 and drawing the contents from one of the 25 containers 18 into the interior of the barrel. The needle is then applied to the patient in the usual manner, and the plunger depressed, thereby effecting the desired bath. If it is desired to apply the contents 30 of the other container 18, this may be done without removing the needle 20 from the patient, by turning the plug or valve 15 so that the passage 16 therethrough opens the passage 12 in the nipple 11 connected 35 to the tube 17 of said other container in communication with the inlet passage 13 in the stem 10. The aforesaid operation is then repeated which causes the liquid in this other receptacle to be drawn into the interior 40 of the barrel and from there expelled.

From the foregoing description, it may be seen that the objects of the invention have been effectively carried out as the device can be refilled without removing the needle 45 from the body of the patient, and further-

more, it can be supplied with the contents of either one of a plurality of containers without considerable trouble.

As various changes in form, proportion, and in the minor details of construction may be resorted to without departing from the spirit of this invention, I do not wish to be limited to the construction herein shown and described, other than that set forth in the appended claim.

60 I claim:

A device of the class described comprising a tubular barrel provided with an integrally formed head at one of its ends and having a handle and a stem extending from 65 diametrically opposite points at the other end thereof, said head being provided with a recess in its outer side, a central opening disposed between the recess and the interior of said barrel, a notch in one edge of the 70 outer side of said head, and a passage disposed between said notch and said recess, said stem and said barrel being provided with communicating passages, the passage in said barrel extending longitudinally 75 through the wall of the same and communicating with the recess in said head, valve seats formed in the recess and notch and registering with the above mentioned passages leading into the same, a cap threaded 80 upon the first mentioned end of said barrel and coöperating with the recess and notch in said head to form inlet and outlet valve compartments respectively, said cap being provided with a nozzle member and having 85 a passage therein disposed between the latter and the notch in the head of said barrel, inwardly and outwardly opening ball valves disposed in the inlet and outlet valve compartments respectively, and a plunger slid- 90 able in said barrel and provided with an operating handle extending to the exterior of the same.

In testimony whereof I have hereunto set my hand in the presence of two subscribing 95 witnesses.

ALFRED N. BESSESEN.
